Primary Examiner — Caron D Veynar*Assistant Examiner* — Katrina N Gonzalez(74) *Attorney, Agent, or Firm* — Allen, Dyer, Doppelt, + Gilchrist, P.A.(57) **CLAIM**

The ornamental design for a solid fuel cooking device, as shown and described.

DESCRIPTION

FIG. 1 is a perspective view of a solid fuel cooking device with a cover portion included and shown within an environmental structure;

FIG. 2 is a perspective view with a cover portion attached and shown removed from an environmental structure for clarity of illustration;

FIG. 3 is a top perspective view with a cover portion removed for clarity of illustration;

FIG. 4 is a side view with a cover portion attached;

FIG. 5 is a top view with the cover portion removed for clarity of illustration; and,

FIG. 6 is a bottom view thereof.

The broken lines illustrate parts of the solid fuel cooking device and unclaimed environmental subject matter and form no part of the claimed design.

1 Claim, 6 Drawing Sheets(56)
